[57] CLAIM

The ornamental design for a replica bottle light, as shown and described.

DESCRIPTION

FIG. 1 is a top, left perspective view of a replica bottle light showing my new design;

FIG. 2 is a right side view thereof, the left side being a mirror image;

FIG. 3 is a top plan view thereof;

FIG. 4 is a bottom plan view thereof;

FIGS. 5, 6 and 7 are top, left perspective views of alternate embodiments of FIG. 1, the only difference being a key chain connector;

FIG. 8 is a top, left perspective view of a second embodiment of FIG. 1;

FIG. 9 is a left side view thereof;

FIG. 10 is a front view thereof;

FIG. 11 is a top plan view thereof;

FIG. 12 is a bottom plan view thereof;

FIGS. 13, 14 and 15 are top, left perspective views of alternate embodiments of FIG. 8, the only difference being a key chain connector;

FIG. 16 is a top, left perspective view of a third embodiment of FIG. 1;

FIG. 17 is a right side view thereof, the left side being a mirror image;

FIG. 18 is a top plan view thereof;

FIG. 19 is a bottom plan view thereof;

FIGS. 20, 21, and 22 are top, left perspective views of alternate embodiments of FIG. 16, the only difference being a key chain connector;

FIG. 23 is a top, left perspective view of a fourth embodiment of FIG. 1;

FIG. 24 is a right side view thereof, the left side being a mirror image;

FIG. 25 is a top plan view thereof;

FIG. 26 is a bottom plan view thereof; and,

FIGS. 27, 28, and 29 are top, left perspective views of alternate embodiments of FIG. 23, the only difference being a key chain connector.

The broken line showings herein presented are for illustrative purposes only and do not form a part of the claimed invention.
